Primary Examiner — Barbara Fox*Assistant Examiner* — Katie Stofko(74) *Attorney, Agent, or Firm* — Diederiks & Whitelaw, PLC; John L. Crimmins, Esq.(57) **CLAIM**

The ornamental design for a translucent edible dough product with filling, as shown and described.

DESCRIPTION

FIG. 1 is a top view of a translucent edible dough product with filling according to our new design, with the bottom view being an identical image thereof;

FIG. 2 is side elevational view of the translucent edible dough product with filling of FIG. 1, with the opposite side view being an identical image thereof; and,

FIG. 3 is a perspective view of the translucent edible dough product with filling of FIGS. 1 and 2.

The contrast in shading in the figures represents a contrast in appearance only and does not represent any particular color, material, texture, or finish.
